UNITED STATES PATENT OFFICE.

THOMAS LOCKE WHITE, OF IDAHO CITY, IDAHO.

TRANSMISSION-BAND.

1,198,090.

Specification of Letters Patent. Patented Sept. 12, 1916.

Application filed December 5, 1914. Serial No. 875,643.

To all whom it may concern:

Be it known that I, THOMAS LOCKE WHITE, a citizen of the United States, residing at Idaho City, in the county of Boise 5 and State of Idaho, have invented certain new and useful Improvements in Transmission-Bands, of which the following is a specification.

My invention relates to transmission bands 10 for automobiles, and particularly to that type used on Ford automobiles.

It is well known that the transmission of a Ford automobile comprises three rotating drums: one for the low speed, one for the 15 reverse, and one for the brake. Each of these drums is partially encircled by a band of resilient steel, lined with asbestos or a similar material, and provided at its ends with stationary ears. These drums, bands, 20 and their associated parts to be described are inclosed by a cover provided with a small opening in its top closed by a hand plate. The ears at the left of the bands on the brake and reverse drums bear against 25 bosses on the inner wall of the transmission cover and hold the left ends stationary while the ends carrying the right ears are movable. These pairs of ears are slotted for the 30 reception of rods which pass through these bosses and through other bosses formed on the outer wall of the cover. A spring is disposed around each of these rods between the ears, and the right ears are held in place 35 by nuts threaded upon the rods and engaging washers contacting with the right ears.

In order to reverse the automobile or to apply the brake, it is necessary that these right ears be moved to the left to cause the bands to grip the drums. This is accomplished by means of foot pedals secured 40 upon the outer ends of the rods, the outer faces of the outer bosses and the inner faces of the bosses on the pedals having cam faces whereby forward movement of either pedal 45 will cause the corresponding rod to be moved to the left, with the result that the band will grip the drum. The right ear of the band encircling the middle or low speed drum is held stationary against an adjustable member 50 extending through a boss on the inside and on the outside of the right hand side of the transmission cover, while the free left

ear is engaged by a member secured on the inner end of a rod passing through a boss on the left side of the transmission cover and 55 carrying at its end a foot pedal. This actuating member is moved by a cam action caused by forward movement of the pedal associated therewith. This pair of ears is slotted for the reception of a guide rod and 60 is held apart by a spring. The bands on all the drums are identically the same and are interchangeable from one drum to another. It is well known in the art that after an automobile has been used for a considerable 65 length of time, the asbestos linings of the bands become worn and have to be replaced. Owing to the peculiar construction of the transmission and transmission cover of the Ford automobile, in order to replace any or 70 all of the bands it is necessary to remove and replace the entire transmission cover, an operation requiring several hours to perform.

The object of the present invention is to 75 provide a transmission band for Ford automobiles so constructed that it may be removed and replaced through the small opening in the top of the transmission cover, thereby eliminating the tedious and time 80 consuming operation now necessary.

Essentially, the object of the present invention resides in the provision of a Ford transmission band having one or both ears removable from the body portion of the 85 band.

With this object in view, my invention consists in the novel construction and arrangement of parts to be hereinafter fully and specifically described and illustrated in 90 the accompanying drawings, in which:

Figure 1 is a plan view of the transmission case of a Ford automobile showing the hand plate removed to expose the drums and their associated parts and showing the bands 95 in place constructed in accordance with my invention, Fig. 2 is a cross sectional view on the line 2—2 of Fig. 1 illustrating my novel band as applied to the brake drum, Fig. 3 is a fragmentary side elevation showing the 100 removable ear applied to a band, Fig. 4 is a fragmentary front elevation thereof, and Fig. 5 is a fragmentary top plan view thereof.

Referring more particularly to the drawings, the numeral 1 designates the transmission case of a Ford automobile which comprises the lower portion 2 and the removable cover 3, the cover 3 being provided with the opening 4 closed by a hand plate 5.

The numerals 6, 7, and 8 designate, respectively, the brake, reverse and low speed drums. Each of these drums is encircled by 10 a band 9 having the usual asbestos lining 10 and provided with the ordinary stationary slotted ear 11 and a slotted removable ear 12 to be hereinafter described in detail.

The numerals 13 and 14 designate the 15 foot pedals for contracting the bands 9 on the drums 6 and 7, respectively, by means of the cam members 15 and 16 and the rods 17 and 18 passing through the ears and having nuts 19 threaded upon their ends.

20 Springs 20 are disposed between each pair of ears. The numeral 21 designates the foot pedal for operating the band 9 on the low speed drum 8 by means of the cam actuated member 22 engaging the removable ear 12 25 slidable upon a guide rod 23. A spring 24 is disposed between this pair of ears.

The operation of the drums and their associated parts forms no portion of the present invention and will not be described, although the parts have been described somewhat in detail for the purpose of explaining the application and advantages of applicant's invention.

In order that the ear 12 may be removable, 35 I form one end of the band 9 with upwardly and inwardly extending longitudinal side flanges 25, and form the base of the ear with grooves 26 slidably receiving the flanges 25, forming a dovetail connection. The extreme rear portion of the base of the ear is 40 provided with lateral extensions 27 engaging the rear edges of the flanges 25 for holding the ear in place so that it can be moved in one direction only. The ear 12 is applied 45 to the band 9 by catching the front portions of the grooves 26 under the flanges 25 and moving the ear longitudinally upon the band until the extensions 27 engage the flanges.

Assuming that the transmission of a Ford 50 automobile is equipped with my bands having removable ears, when it is desired to remove a band it is necessary first to remove the hand plate 5 which will expose the interior mechanism to view. Assuming for 55 explanation that it is the brake band which it is desired to remove, the operation is as follows: The nut 19 is then removed from the rod 17, whereupon the foot pedal 13 and the rod 17 may be withdrawn from the side 60 of the transmission cover 3. The ear 12, being the right hand one, is then slid downwardly to the right upon the band 9 to disengage it from the flanges 25 so that it may be entirely removed. The operator then

grasps the stationary ear 11 and pulls upwardly upon it, whereupon the band will slide around the drum. The flexible nature of the band permits its ensuing partial straightening as it is pulled out of the transmission case as shown by the dotted lines 65 in Fig. 2. The band is replaced by inserting its flanged end at the left of the drum and pressing it downwardly, whereupon its natural tendency to conform itself to the drum will cause it to encircle the drum. 70 The band is pushed around in this manner until the ear 11 is in the proper place, after which the ear 12 is reengaged upon the flanges 25. The rod 17 is then reinserted and engaged within the notches in the ears 75 and the nut 19 is again screwed in position. This operation is of course the same for any of the bands.

Having thus described my invention what I claim is:

1. An automobile transmission band provided with a detachable ear, flanges on said band engaging said ear for holding it in position.

2. An automobile transmission band having a rigid ear on one end thereof and a detachable ear on the other end, said detachable ear being held in position by converging flanges formed on said band.

3. An automobile transmission band having a detachable ear on one end thereof, said ear being provided with slots on its sides to engage flanges formed on said band.

4. An automobile transmission band comprising a curved strip of resilient material, 100 an ear rigidly mounted on one end of said band, a second ear slidably engageable upon and removable from the other end thereof, converging flanges on said band, and slots in the sides of said ear for engagement with 105 said flanges.

5. An automobile transmission band comprising a strip of resilient material, an ear rigidly mounted on one end thereof, a second ear slidably engageable and removable 110 from the other end thereof and means for limiting the removal of said second ear in but one direction.

6. An automobile transmission band comprising a curved strip of resilient material, 115 an ear rigidly secured on one end thereof, and an ear slidably engageable upon and removable from the other end thereof.

7. An automobile transmission band comprising a curved strip of resilient material, 120 an ear rigidly secured on one end thereof, converging flanges on the sides of the other end thereof, an ear provided with grooves engageable with said flanges, and lateral extensions on said ear engaging the rear 125 ends of said flanges, whereby said second named ear may be removed from said band by longitudinal movement in one direction.

8. An automobile transmission band comprising a strip of resilient material and an ear slidably engageable thereon.

9. An automobile transmission band comprising a strip of resilient material, and an ear slidably engageable upon and removable therefrom.

In testimony whereof I hereto affix my signature in the presence of two witnesses.

THOMAS LOCKE WHITE.
